UNITED STATES PATENT OFFICE

149,455

DESIGN FOR AN AUXILIARY CRADLE FOR TELEPHONE HANDSET

Harwood B. Stofer, Lakewood, Ohio

Application January 9, 1947, Serial No. 136,022

Term of patent 3½ years

(Cl. D48—14)

To all whom it may concern:

Be it known that I, Harwood B. Stofer, a citizen of the United States of America, residing at Lakewood, in the county of Cuyahoga and State of Ohio, have invented a new, original, and ornamental Design for an Auxiliary Cradle for Telephone Handset, of which the following is a specification, reference being had to the accompanying drawing, forming a part thereof, in which:

Figure 1 is a perspective view of an auxiliary cradle for telephone handset embodying the present invention.

Fig. 2 is a top plan view of the auxiliary cradle shown in Fig. 1; and

Fig. 3 is a side elevational view of the auxiliary cradle shown in Fig. 1.

I claim:

The ornamental design for an auxiliary cradle for telephone handset, substantially as shown.

HARWOOD B. STOFER.
